(57) **CLAIM**

We claim the ornamental design for a milking claw, as shown and described.

DESCRIPTION

FIG. 1 is a side elevation view of a milking claw in accordance with the present invention;

FIG. 2 is a front perspective view of the claw body portion of the milking claw, shown separately for clarity of illustration;

FIG. 3 is a top plan view of the claw body portion of the milking claw, shown separately for clarity of illustration;

FIG. 4 is a front perspective view of the bowl portion of the milking claw, shown separately for clarity of illustration;

FIG. 5 is a side perspective view of the milking claw;

FIG. 6 is a front elevation view thereof;

FIG. 7 is a side elevation view thereof;

FIG. 8 is a rear perspective view thereof;

FIG. 9 is a top plan view thereof; and,

FIG. 10 is a bottom view thereof.
